UNITED STATES PATENT OFFICE.

MINUS CARR, OF MAUD, MISSISSIPPI.

SWITCH.

1,213,073.

Specification of Letters Patent. Patented Jan. 16, 1917.

Application filed January 28, 1916. Serial No. 74,817.

To all whom it may concern:

Be it known that I, MINUS CARR, a citizen of the United States, residing at Maud, in the county of Tunica and State of Mississippi, have invented new and useful Improvements in Switches, of which the following is a specification.

This invention relates to a controller for electrical ignition systems and has for its 10 primary object to provide a controller having the inherent property of breaking a battery circuit of the ignition system when the speed of the vehicle in case of an automobile, has reached a predetermined degree and at 15 the same time close the magneto circuit and may also accomplish the additional advantage of rendering both the battery and magneto circuits inactive upon the speed of the vehicle reaching above a second predetermined degree.

My invention also contemplates the use of locking means for locking a portion of the device against further movement upon one operation of the ball governor, an object of the 25 invention being the provision of two solenoids controlling the operation of an arm toward the magneto circuit closing position or a battery circuit closing position, one of the solenoids being manually controlled while the 30 other solenoid is mechanically controlled, that is to say, the energization of the solenoid for throwing the arm to a position to close the battery circuit being manually controlled, while that solenoid moving the arm 35 to a position to close the magneto circuit being mechanically controlled, the mechanism for controlling this solenoid depending for operation upon the speed of rotation of the drive shaft of the engine.

40 My invention also contemplates the use of auxiliary switches for rendering a portion of the governor inactive in case of rupture of a portion of the controller or the refusal to work of the magneto.

45 My invention also makes use of means for allowing the governor to accommodate various speeds. In order that the principles of my invention may be clearly understood I have disclosed a single type or embodiment 50 thereof in the accompanying drawings, wherein:—

Figure 1 is a diagrammatic view of the system. Fig. 2 is a top plan view of the solenoid control mechanism. Figs. 3 and 4

are sectional views therethrough. Fig. 5 is 55 a longitudinal sectional view of the governor casing, the mechanism being shown in side elevation. Figs. 6, 7, 8 and 9 are detailed sectional views through Fig. 5. Fig. 10 is a view similar to Fig. 1 showing one position 60 of the governor and one position of the circuit controlling arm, the direction of current being shown by arrows. Fig. 11 is a sectional view on the line 11—11 of Fig. 9.

In the drawings, the numeral 1 designates 65 the well known form of magneto, the numeral 2 a self-starting motor for the internal combustion engine and the numeral 3, the ordinary dry batteries of the ignition system.

70 In the drawings and description, I have eliminated the spark plugs and their connection as I deem it is unnecessary in the disclosure of my invention.

The base 4 has mounted thereupon, the 75 bearings 5, 6 and 7, the first of which has journaled therein, a shaft 8 having a gear connection with the shaft of the internal combustion engine with which the ignition system coöperates. The shaft 8 has rigidly 80 secured thereto a pair of governors 10 and 11, the latter being of a size smaller than the former, and both arranged at 90 degrees in position from each other. The governor 10 has a rotatable connection with a collar 12 85 secured to a rod 13 that telescopes within the shaft 8 and the hub portion of the governor 10 and the governor 11 has a similar connection 14 with a sleeve 15 slidably mounted within the bearing 6 and slidably supports 90 the rod 13.

The sleeve 15 has encircling it between a nut 16 and the adjacent side of the bearing 6, a coiled spring 17, the purpose of which is to hold the balls of the governor 11 in a 95 retracted position which results in the switch 18 that has a pivotal connection with one end of the sleeve being normally held closed, that is to say in a closed position until the balls of the associated governor 100 reach a predetermined outward position, the switch 18 being mounted on a bracket 20 in spaced relation to a second switch 21, the action of which being under the control of the sliding movement of the rod 13.

105 To distinguish between the switches throughout the remaining portion of the specification and claims, I have designated

the former a battery switch while the latter a magneto switch thus indicating that portion of the ignition system controlled by these switches. Encircling the intermediate portion of the rod 13 is a coiled spring 22 that has its opposite ends abutting an extension 23 of the bracket 20 and a nut 24 adjustable on the rod, the purpose of the latter being to increase the tension of the 5 spring at will for controlling the centrifugal action of the balls of the governor 10 for a purpose hereinafter described.

The protruding end portion of the rod 13 has secured thereto, an L-shaped finger 25, 15 the long arm of which being movably mounted in a slot 26 formed in one end of a pawl 27 that is in turn slidably mounted in a post 28. The short arm of the finger 25 terminates in a hook 29, one face of 20 which being arranged at an incline so as to give a cam action to the adjacent end of a dog 30 pivoted intermediate of its ends and having its bill 31 coöperating with the teeth 32 formed on the periphery of a disk 25 33. This disk 33 is rigidly mounted upon a shaft 34 that in turn rigidly supports a ratchet wheel 36, the teeth of which co-operate with the pawl 27 and also mounted on the shaft 34 is a circuit closing device 37. 30 This circuit closing device 37 has one of its elements formed in the shape of a wheel 38, the rim of which is made of insulating material as well as the hub, or as illustrated in the drawings, a portion of the hub, while 35 the spokes 39 are made of conducting material of low resistance such as copper. The other element of the circuit closing device 37 is in the form of a brush 40 so arranged to engage the spokes as they move in a circular path.

From the description it will be seen that during the rotation of the shaft 8 through the action of the drive shaft of the internal combustion engine, the balls of the governors 10 and 11 will be thrown outwardly and through their connections with the sleeve and rod 13, the sleeve and rod will be given a sliding movement which movement will be transmitted to the battery circuit closing switch and the magneto circuit closing switch, the former closing at a relatively slow number of revolutions of the shaft 8, while the latter closes at a relatively higher revolution. Thus it will be seen that initially, the battery circuit of the ignition system is closed while subsequently, the magneto circuit is closed or as illustrated in the drawings, partially closed, as the circuit closing device 37 controls the closing of a portion of the magneto circuit in a manner to be described later. Upon the rod 13 sliding a predetermined distance the inclined face of the finger 25 will depress the adjacent end of the dog 30 with the result that the bill 31 is retracted from

the teeth of the disk 33. Subsequently to this action, the pawl 37 gives a partial rotation to the ratchet 36. This rotary action of the ratchet 36 gives a partial rotation to the wheel 38 of the circuit closing device 37, 70 with the result that one of the spokes is brought into electrical contact with the brush 40 for completing the closing of the magneto circuit.

Coöperating with the switches 21 and 18 75 for closing the circuit of the battery and magneto as each is broken at two points, is a switch arm 41 pivoted to a support 42 as indicated at 43. Arranged contiguous to the pivot 43 is a pair of spring pressed contacts 44 adapted to coöperate with a suitable key in a manner hereinafter described. These contacts 44 are arranged in a partial circuit 45 attached onto the circuit 46 and includes a battery 47 and the starting motor 80 2. Arranged in this circuit 46 between the partial circuit 45 and the battery 47 is a push button 48 or other form of manually operated switch. Thus it will be seen that when a key is inserted between the spring pressed 90 contacts 44 for bridging a break in the circuit 45 at this point, and then depressing the push button 48 current will flow from the battery 47 through the solenoid 49 and simultaneously the current will pass through 95 the starting motor for turning over the internal combustion engine. Upon energization of the solenoid 49, its core is sucked inwardly and as this core is pivotally connected to the switch arm, the latter will be moved toward the solenoid so as to deposit one extremity upon the contact 51 forming the terminal for the wire 52 leading from the battery 3. Simultaneously with this 100 action, the remaining terminal or end of the switch arm engages the contact 52 that is in turn connected by means of a wire 53 with an arcuate-shaped contact 54. Normally engaging the contact 54 is an auxiliary switch 55 the pivot of which is connected by a wire 105 56 leading to the battery switch controlled by the governor. The battery switch of the governor is connected to the magneto by way of the conductor 57. A second solenoid 58 is arranged in axial alinement with the solenoid 49 and has its core 59 arranged in alinement with the core 50 and attached to the switch arm at the same point. This solenoid 58 is arranged in a circuit 60 receiving current from the battery 47 and 110 adapted to be closed by the circuit closing device 37, when one of the spokes engages the brush 40 in the manner previously set forth. Upon the energization of the solenoid 58 which takes place when the device 115 37 is moved by the governor, the switch arm is thrown to a position to engage a contact 61 to which is connected the wire 62 running from the magneto 1. The switch arm 41 also engages another contact 62 that is 120 125 130

joined to a second arcuate-shaped contact 53 by means of a wire 64. Normally engaging the contact 63 is an auxiliary switch 64 electrically connected in the magneto switch 5 controlled by the governor by means of the conductor 65. The connection between the switch controlled by the governor and the magneto is made by means of a wire 66. In case of a defect in the governor and its 10 associate parts I provide means for short circuiting, the magneto switch and the battery switch being controlled by the governor. I accomplish this by arranging contacts 67 and 68 which are engaged by the auxiliary 15 switches 55 and 64 when they are moved in one direction out of engagement with the contacts 63 and 54. These contacts 67 and 68 are connected respectively with the conductors 66 and 57 tapped onto the conductors 20 57 and 66.

I will now give a brief description of the operation of my device.

In starting the system into operation, the operator presses the push button 48 with 25 the result that current from the battery 47 passes through the motor and simultaneously through the solenoid 49 which energizes the solenoid, as previous to this, the operator has inserted a key so as to bridge 30 the distance between the contacts 44. At this point I wish it to be understood that the same key may be utilized for moving the auxiliary switches 55 and 64 to a position 35 engaging the contacts 67 and 68 or by a separate key that fits the auxiliary switches 55 and 64, the construction of such special key is such that the removal of the same will move the auxiliary switches 55 and 64 into engagement with contacts 63 and 54 where- 40 upon the ball governors 10 and 12 will be rendered active. It is to be understood that the first special key does not operate both of the auxiliary switches simultaneously but 45 separately one at a time. Upon the energization of the solenoid 49, the switch arm is thrown into the position to throw the battery 3 in circuit for energizing the spark plugs, the current then passing through the battery switch controlled by the governor. 50 As the speed of the engine increases, the battery switch 18 is broken by the associated governor which may be so regulated as to happen when the engine is making about 150 revolutions a minute. As the speed of 55 the engine continues to accelerate, the battery switch having been broken the next action will be upon the magneto switch 21. We will assume that the apparatus is regulated for stopping the engine upon reaching 60 above 500 revolutions a minute. As soon as this speed is reached, the governor associated with the magneto switch moves it to open position with the result that the spark plugs are deenergized for cutting off energy 65 supply to the engine. It is to be under-

stood of course that previous to current passing from the magneto to the spark plug, the pawl 27 has moved the ratchet 36 one point for throwing into engagement one of the spokes of the circuit closing device 70 and the brush for energizing the solenoid 58 which draws the switch arm to a position to bridge the break in the magneto circuit at the switch arm.

Having thus described one type or embodiment of my invention I desire it to be understood that although specific terms are employed, they are used in a generic and descriptive sense and not for the purpose of limitation, the scope of the invention being set forth in the following claims.

What is claimed is:

1. A controller for electrical ignition systems comprising a ball governor, a switch, an electro-mechanical means coöperating 85 with said governor and switch for alternately throwing the battery and magneto of the ignition system in circuit with the spark plugs, means for short circuiting said switch independent of said governor.

2. A controller for electrical ignition systems comprising a ball governor, a switch, an electro-mechanical means coöperating with said governor and switch for alternately throwing the battery and magneto of 95 the ignition system in circuit with the spark plugs, and lock controlled means for short circuiting said switch.

3. A controller for electrical ignition systems comprising a ball governor, a magneto 100 switch and a battery switch controlled by said governor, an electro-mechanical means acting through said switches for alternately connecting the battery or magneto of the ignition system in circuit with the spark 105 plugs, and an auxiliary switch for short circuiting said magneto and battery switches.

4. A controller for electrical ignition systems comprising a ball governor, a magneto switch and a battery switch controlled by 110 said governor, an electro-mechanical means acting through said switches for alternately connecting the battery or magneto of the ignition system in circuit with the spark 115 plugs, and independent auxiliary switch for each of said magneto and battery switches for short circuiting the same.

5. A controller for electrical ignition systems including a battery and a magneto comprising a variable speed device, electro-mechanical means for alternately connecting the battery or magneto of the ignition system in circuit with the spark plug, and self-locking means under the control of said governor for rendering a portion of said first 125 means active.

6. A controller for electrical ignition systems including a magneto and battery comprising a variable speed device, a magneto switch and a battery switch controlled by 130

- said device, electro-mechanical means for alternately connecting the battery or magneto with the spark plug, and means operated by a key for throwing a portion of said means in circuit with said battery.
7. A controller for electrical ignition systems including a magneto and battery comprising a variable speed device, a magneto switch and a battery switch controlled by said device, electro-mechanical means for alternately connecting the battery or magneto with the spark plug, and rotary means operated by the said device for rendering a portion of said first means active.
- 10 8. A controller for electrical ignition systems including a magneto and battery comprising a variable speed device, a magneto switch and a battery switch controlled by said device, electro-mechanical means for alternately connecting the battery or magneto with the spark plug, and rotary means operated by said governor for momentarily rendering a portion of said first means active.
- 15 9. A controller for electrical ignition systems including a magneto and battery comprising a variable speed device, a magneto switch and a battery switch controlled by said device, electro-mechanical means for alternately connecting the battery or magneto with the spark plug, and self locking rotary means operated by said device for
- 20 10. A controller for electrical ignition systems including a magneto and battery comprising a variable speed device, a magneto switch and a battery switch controlled by said device, electro-mechanical means for alternately connecting the battery or magneto with the spark plug, and self locking rotary means operated by said device for momentarily rendering a portion of said first means active, said first means including a pawl and ratchet.
- 25 11. A controller for electrical ignition systems including a magneto and battery comprising a variable speed device, a magneto switch and a battery switch controlled by said device, electro-mechanical means for alternately connecting the battery or magneto with the spark plug, and self locking rotary means operated by said device for momentarily rendering a portion of said first means active, said last means including a pawl and ratchet and a dog for limiting the movement of said ratchet.
- 30 In testimony whereof I affix my signature in presence of two witnesses.

MINUS CARR.
